UNITED STATES PATENT OFFICE.

SAMUEL R. KRAMER, OF PERKASIE, PENNSYLVANIA, ASSIGNOR TO EASTERN PIN TICKET AND TAG CO. INC., OF PERKASIE, PENNSYLVANIA, A CORPORATION OF PENNSYLVANIA.

LABEL CABINET.

Application filed March 28, 1921. Serial No. 456,394.

To all whom it may concern:

Be it known that I, SAMUEL R. KRAMER, a citizen of the United States, residing at Perkasie, in the county of Bucks, State of Pennsylvania, have invented a new and useful Label Cabinet, of which the following is a specification.

My invention consists of a device for conveniently presenting labels of various purposes as required, the same embodying a cabinet adapted to support boxes in which labels of different characteristics are contained, said boxes being provided with outlets through which required labels as required may be successively withdrawn and delivered for attachment to a place of service without displacing the boxes from the cabinet, thus providing a convenient, handy, practical, efficient and attractive device for the business of shipping, packing and other purposes.

The invention is satisfactorily illustrated in the accompanying drawings, but the important instrumentalities thereof may be varied, and so it is to be understood that the invention is not limited to the specific details shown and described, as long as they are within the spirit or scope of the claim.

Figure 1 represents a perspective view of a label cabinet embodying my invention.

Figure 2 represents a perspective view of one of the boxes employed, the same being in open condition.

Figure 3 represents a horizontal section on line 3—3 Figure 4.

Figure 4 represents a vertical section on line 4—4 Figure 3.

Similar numerals of reference indicate corresponding parts in the figures.

Referring to the drawings.

1 designates a cabinet with shelves 2 therein, 3 designates a series of boxes which are adapted to be placed in the cabinet side by side on said shelves, and the bottom of the cabinet and adapted to contain rolls 4 of labels, the fronts of said boxes having pasted or gummed thereon the labels 5 which indicate the nature of the labels of the rolls within the boxes.

50 The labels of the rolls are printed on

strips of paper or other material perforated between adjacent labels as at 6 so that a label may be readily torn off and used for the respective purpose, thus the box in the lower right corner of the cabinet, Figure 1, 55 contains a roll of labels for work requiring "rush," and so the label 7 torn off the roll in said box has printed thereon the word "Rush" corresponding to the indicating label on the box. 60

As the torn off label has on its back gum or other adhesive material, the latter may be moistened when the label is in condition to be attached to its place of service.

In order to withdraw the required labels 65 from the boxes the latter has each in its side the throat 8 through which a label may be withdrawn, the roll unwinding or unrolling in the box, and then when it is out to the required extent, it may be torn off on either 70 side wall of said throat as a bearing therefor on the line of perforations 6 when a short stub of the next label may remain in the throat ready to be engaged by the fingers or nails of the hand of the operator so that 75 said next label when required may be drawn out through the throat, without interference of the adjacent box or the removal of either box.

Attention is drawn to the fact that the 80 front wall of a box is foreshortened and a sliding lid 9 comprises a side of the box, said lid when open providing access to the interior of the box to supply the latter with a roll of labels, said lid having on its top, 85 bottom and inner edges the tongues 10 which may enter grooves 11 in the top, bottom and rear walls of the box to retain the lid on the box and permit it to be slidable out and in.

When the box is closed, the front end portion 12 of the lid is adjacent to the throat 8 and so comprises a wall of said throat whose other wall is the foreshortened end of the front wall of the box, hence said throat has opposite walls on the sides thereof 95 against which the label may be pressed at the perforations 6 to strip it off when drawn out.

The rolls are well inclosed in the boxes and protected in the main from dust, es- 100

especially the pasted or gummed sides thereof, and thus the labels are kept in sanitary condition.

Having thus described my invention what 5 I claim as new and desire to secure by Letters Patent, is—

A box adapted to contain continuous labels detachable from each other, having on one side a sliding lid, and in a wall an exit 10 throat, the latter being formed by fore-

shortening said wall towards the outer terminal of said lid, the edge of said foreshortened wall comprising one side of said throat and the inner face of the outer terminal of said lid comprising the other side 15 of said throat.

SAMUEL R. KRAMER.
